UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed September 4, 1919. Serial No. 321,684.

To all whom it may concern:

Be it known that I, ALFRED G. F. KUROWSKI, a citizen of the United States, formerly a citizen of Germany, residing in Brooklyn 5 Borough, in the county of Kings, city and State of New York, have invented certain new and useful Improvements in Typewriting Machines, of which the following is a specification.

10 This invention relates to key-tops for typewriter key-levers, an object of the invention being to provide an extremely simple structure, whereby, without tools of any kind, the operative may change the key-papers, at 15 will.

A feature of the invention consists in providing a key-cup which is screw-threaded and a key-ring correspondingly screw-threaded, between which cup and ring the 20 key-paper and glass are held.

Other features and advantages will herein-after appear.

In the accompanying drawings,

Figure 1 is a perspective view of a key-25 lever, showing my invention applied thereto.

Figure 2 is a composite view.

Figure 3 is a part sectional, part elevational view.

Referring to the drawings, the key-lever 1 30 has a key-cup 2 mounted on its stem. Said cup, as usual, fits tightly on the key-stem, and is provided on its flange with screw-threads 3, the flange being of sufficient height to hold within it the usual key-glass 4 and

key-paper 5. In order to securely hold the 35 glass and paper, and also to provide means for readily obtaining access to the papers, in order to substitute different papers or a blank, as desired, a key-ring 6 is provided, having screw-threaded portions 7, which engage the screw-threaded flange 3 of the cup. The key-cup and key-ring are made of light sheet-metal and the threads are rolled therein. To change the key-papers, the ring is 40 unscrewed, and, after a new paper or blank 45 is inserted, the ring is again screwed to the cup.

Variations may be resorted to within the scope of the invention, and portions of the 50 improvements may be used without others.

Having thus described my invention, I claim:

The combination with a typewriter key lever of a cup fixed against rotation on said lever, the sides of the cup being made from 55 thin sheet metal, said metal sides having a screw-thread rolled therein, a key-paper and glass inserted in said cup, and an annular cap also of thin sheet metal and having threads rolled in the sides thereof and adapted to be screwed down upon said cup, said cap having an inturned top flange to bear 60 down upon the glass to retain the glass and paper in the cup.

ALFRED G. F. KUROWSKI.
